UNITED STATES PATENT OFFICE.

THOMAS ELSWORTH BLAUVELT AND JOHN JACKSON FOOSHEE, OF HURLEY, NEW MEXICO.

FLUE-CLEANER.

1,271,656.

Specification of Letters Patent. Patented July 9, 1918.

Application filed March 22, 1917. Serial No. 156,713.

To all whom it may concern:

Be it known that we, THOMAS E. BLAUVELT and JOHN JACKSON FOOSHEE, citizens of the United States, residing at Hurley, in the county of Grant and State of New Mexico, have invented certain useful Improvements in Flue-Cleaners, of which the following is a specification, reference being had therein to the accompanying drawing.

10 The invention relates to a flue cleaner.

The primary object of the invention is the provision of a flue cleaner wherein soot, ashes, dust or the like accumulated within a flue can be readily and easily removed with despatch without possibility of the flying particles scattering or permeating the atmosphere, and also eliminating the soiling of the hands and the clothes of the user.

Another object of the invention is the provision of a flue cleaner of this character which is simple in construction, thoroughly reliable and efficient in use, readily and easily operable and inexpensive in manufacture.

25 Other objects will be in part obvious and in part hereinafter set forth.

The invention accordingly consists in the features of construction, combination of elements and arrangement of parts which will be exemplified in the construction herein-after described, and the scope of the application of which will be indicated in the appended claim.

In the accompanying drawings:

35 Figure 1 is a fragmentary sectional view through a ceiling with a flue in elevation, showing the cleaner constructed in accordance with the invention applied;

40 Fig. 2 is an enlarged vertical sectional view through the cleaner;

Fig. 3 is a perspective view of the scraper or wiper used with the flue cleaner.

Similar reference characters indicate corresponding parts throughout the several

45 views of the drawings.

Referring to the drawings in detail, A designates a portion of a flue which is mounted in the ceiling of a room or inclosure in the ordinary well known manner, with the end of the flue protruded a distance beyond said ceiling for the attachment of a stove pipe to the flue, as usual.

50 The flue cleaner comprises a thimble or sleeve 5 which is formed with a staff 6 constituting a handle, and which may be of

any desired length for permitting the proper reach in the use of the cleaner, as hereinafter described.

Connected to and depending from the thimble or sleeve 5 is a tubi-form sack or bag 7 made from fabric, although it may be made from other flexible material and constitutes a receiver for soot, ashes, dust or other like matter, the open end of the sack or bag 7 in this instance being formed with a casement 8 which receives the thimble or sleeve 5, and in this manner the latter reinforces the same so that it may be telescoped on to the protruded end of the flue, although said sack or bag can be otherwise mounted, and when carried by the thimble or sleeve and engaged on the flue will serve to catch the scrapings or wipings from within the same for the cleaning of the flue, the handle being designed to permit the application of the flue cleaner to the flue when the latter is in or beyond reach.

Formed in the body of the sack or bag 7 is a reinforced eyelet 9, through which slides the stem 10 of a wiper or scraper which is formed with a ring-like head 11 at right angles to the stem 10, and upon this head is adapted to be wrapped a suitable cloth, and on reciprocating the scraper or wiper the soot, ashes, dust or the like can be removed from the wall of the flue interiorly thereof and deposited or caught within the bag or sack, in this manner enabling the thorough cleaning of the flue with despatch without possibility of the scattering of the scrapings or wipings or the permeating of the atmosphere therewith and the soiling of the hands and clothes of the user of the cleaner.

From the foregoing description, taken in connection with the accompanying drawing, the construction and manner of use of the herein described flue cleaner will be readily apparent and, therefore, a more extended explanation has been omitted.

Having thus described our invention, we claim:

A flue cleaner of the character described, including a receiving sack, the body of which is formed with an eyelet, the upper portion of the body of the sack being folded inwardly upon itself, and secured to the main portion of the body to form a casement, a supporting thimble mounted within the casement and snugly engaged thereby and serving to reinforce the sack and hold

the upper portion thereof extended, an elongated handle having the upper end rigidly connected to the thimble while the main portion depends therefrom and is arranged in close relation to the thimble and the sack for facilitating the telescoping of the thimble on the flue, the thimble serving to hold the inner portion of the casement in close

relation to the flue, a scraping element disposed within the sack and a stem on the 10 scraping element projected through the eyelet.

In testimony whereof we affix our signatures.

THOMAS ELSWORTH BLAUVELT.
JOHN JACKSON FOOSHEE.
